UNITED STATES PATENT OFFICE.

JULIUS H. WALD, OF CHICAGO, ILLINOIS.

BAG-TYING MACHINE.

Application filed March 31, 1925. Serial No. 19,751.

My invention relates to bag tying machines.

One of the objects of my invention is to provide a machine for tying tea bags which will tie them at a rapid rate.

A further object of my invention is to provide a machine for continuously making a bag tie such as is disclosed in the application of Malm, Serial No. 645,789, filed June 16, 1923.

Further objects of my invention will appear from the description and claims.

In the drawings, in which my invention is illustrated;

Figure 1 is a sectional side elevational view of a bag tying mechanism and associated parts;

Fig. 2 is a plan view of parts shown in Fig. 1;

Fig. 3 is a plan view of the needle and reciprocating shuttle holder;

Fig. 4 is a section on the line 4—4 of Fig. 3;

Fig. 5 is a plan view of part of the intermittently movable conveyor which carries the bags;

Fig. 6 is a section on the line 6—6 of Fig. 5;

Fig. 7 is an end view of Fig. 5;

Fig. 8 is a plan view of the shuttle or looper;

Fig. 9 is an edge view of the looper;

Fig. 10 is an elevational view of the reciprocating needle carriage and the rock arm for drawing up the loop;

Fig. 11 is a plan view showing the reciprocable looper mechanism engaging the bag carrying conveyor;

Fig. 12 is a view similar to Fig. 11 showing the looper initially engaging the thread;

Fig. 13 is a similar view showing the looper beginning to make the loop; and

Fig. 14 is a similar view showing the thread about to slip off from the looper to complete the loop.

Referring to the drawings in detail, the bag tying machine shown comprises an intermittently movable conveyor 10 provided with a series of bag carrying and neck gathering devices 11 and a bag tying mechanism past which the bags are carried, comprising a reciprocable needle 12 which perforates the gathers at the neck of the bag and forces a loop of cord therethrough during the stationary condition of the conveyor, an intermittently reciprocable loop placing mech-

anism 13 which catches hold of the thread after it has been forced through the neck of the bag by the needle and places a loop about the neck of the bag, this loop placing mechanism being reciprocable to bring the axis of the shuttle in line with the neck of the bag during the stationary condition of the conveyor, and to move the loop placing mechanism out of the way of the conveyor after the loop has been completed to permit the further intermittent movement of the conveyor, means 14 for intermittently gripping the thread being fed to the needle, and means 15 acting on the thread between this gripping means and the needle for drawing the loop up about the neck of the bag.

The intermittently movable conveyor comprises a pair of conveyor chains 16 which are intermittently driven at the proper time by suitable mechanism (not shown).

Each bag carrying and neck gathering device 11 mounted on the conveyor comprises a grooved guide member 17 extending transversely of the conveyor chains and a pair of neck closing and gathering jaws 18 reciprocable in the transversely extending guide for squeezing the neck of the bag together and holding it during the tying operation. These closing jaws are controlled in their sliding movement by means of suitable cams (not shown) acting on the follower members 19. When the bag carrying device is brought opposite the bag tying mechanism the cams will have moved the closing jaws to the position shown in Fig. 11, in which position the neck of the bag will be gathered tightly in position for the needle to force a loop of thread therethrough.

The needle 12 which forces the loop of thread through the neck of the bag is mounted on a reciprocable needle block or carriage 20 which is intermittently reciprocated by means of a sprocket wheel 21 having a crank pin 22 which engages a cam groove 23 in the side of the needle carriage (Fig. 10). This sprocket wheel 21 is driven from the drive shaft 24 by means of a sprocket chain 25 and a sprocket 26 mounted on the drive shaft. The cam groove 23 is so shaped as to give a quick movement to the needle carriage when the crank pin is travelling from 27 to 28 and from 29 to 30, the other parts of the cam groove being arcuate so as to constitute a "dwell", causing no movement of the needle carriage. The thread is drawn by the bag tying mechanism from a spring

- tension device 31 through the intermittent gripping device 14 through a loop 32 in a light spring arm 33 and through an opening in an oscillatable rock arm 34 which acts to draw up the loop about the neck of the bag, as hereinafter described, through a groove 35 in the needle carriage to the eye of the needle, which brings the thread in a position to be operated on by the loop placing mechanism 13.
- This loop placing mechanism comprises a reciprocable looper carriage 36 which is intermittently reciprocated to bring the axis of the looper or shuttle 37 into line with the neck of the bag for the looping operation during the stationary condition of the conveyor and is moved out of the way of the conveyor after the looping operation is performed to permit the step by step movement of the conveyor. This looper carriage 36 is moved back and forth by means of a tension spring 38 tending to pull in one direction and a cam 39 mounted on the drive shaft 24, which cam engages the roller follower 40 on the looper carriage to move it against the action of the spring 38.
- The looper or shuttle 37 shown in Figs. 8 and 9 is rotatably mounted in a circular seat or depression 41 in the looper carriage. The looper carriage in its reciprocating movement moves the looper or shuttle into or out of driven relationship with respect to the vertical shuttle drive shaft 42. In order to hold the shuttle in place in the circular depression 41, a light leaf spring 43 is provided which engages the upper portion of the shuttle and holds it in place when it is out of driven relationship with respect to the drive shaft 42.
- The successive stages of the operation of the looper or shuttle are shown in Figs. 11, 12, 13 and 14. In Fig. 11 the looper carriage has been shifted so that the axis of the shuttle is in alignment with the neck of the bag, the looper carriage being provided with a pair of rollers 44 which straddle the slide 17 which carries the bag and snugly engage the edges thereof to insure proper alignment of the shuttle with respect to the neck of the bag. The shuttle drive shaft 42 is intermittently driven as will be explained in detail hereinafter, and begins to rotate the shuttle after the shuttle has aligned itself with the neck of the bag. In Fig. 12 the shuttle has rotated somewhat from the position shown in Fig. 11 and is just beginning to pick up the thread 45 from the needle, the thread being received in the notch 46 formed in the point of the looper. Fig. 13 shows the shuttle rotated still further and shows the looper beginning to wrap the cord about the neck of the bag at 47. Fig. 14 shows the looper about to complete the looping operation, the cord being wound about one-half way around the neck of the bag at 48, the portion of the cord which lies on top of the shuttle being about ready to slip off from the shuttle between the upper surface of the shuttle and the lower end of the drive shaft 42. The engagement between the drive shaft and shuttle is loosened at this point to permit the cord to slip therebetween. That part of the cord referred to lying above the shuttle is caused to slip between the shuttle and the drive shaft at this point in the operation by means of the loop tightening arm 34 on the needle carriage which is operated at this point to act on the cord between the intermittently acting cord grip 14 and the needle, as described in detail hereinafter.
- The drive shaft 42 for the shuttle drives the shuttle by means of a sleeve or collar 49, splined to the shaft and having a driving lug or projection 50 which engages a corresponding driving lug or projection 51 on the shuttle. The drive collar 49 is held in accurate driving relation with respect to the shuttle during the rotating movement of the shuttle by means of a fixed pin 52, which engages the upper shoulder of this driving collar and prevents its rising up on the drive shaft. However, the drive collar is provided with a notch or depression 52a at the proper point, which comes opposite the fixed pin 52 after the shuttle has finished its rotating movement and this notch permits the drive collar to yield upwardly to permit that part of the cord 45 which lies above the shuttle to slip easily between the upper face of the shuttle and the lower end of the drive shaft and drive collar. This vertical shuttle drive shaft is intermittently driven from the drive shaft 24 by means of a spiral gear 53 on the drive shaft, a spiral gear 54 driven from the spiral gear 53, a mutilated gear 55 mounted on the same shaft as the spiral gear, a pinion 56 intermittently driven from this mutilated gear 55, a shaft 57 on which this pinion is mounted, a bevel gear 58 mounted on this shaft 57 and a bevel gear 59 meshing with this bevel gear 58 and mounted on the vertical shuttle drive shaft 42.
- The loop take-up arm 34 is pivotally mounted on the needle carriage by means of a pivot pin 60 and is controlled in its oscillating movement by means of a tension spring 61 urging it in one direction and a rock lever 62 which controls the spring actuated movement of the loop take-up lever. This rock lever 62 is pivoted on a fixed support 63 by means of a pivot screw 64 and is actuated by the movement of the needle carriage 20. When the needle carriage moves to the right from the position shown in Fig. 10 to the position shown in Fig. 1, the left-hand end of the rock lever drops down when the left-hand end of the

needle carriage passes the shoulder 65 on the rock lever. This permits the tension spring 61 to move the loop take-up lever 34 to the position shown in Fig. 1. When the 5 needle carriage starts to move to the left from the position shown in Fig. 1, the left-hand end of the rock lever 62 is at once forced upwardly, causing the right-hand end to move downwardly and quickly move the 10 loop take-up lever 34 back to the position shown in Fig. 10, which causes the portion of the cord which lies above the shuttle to be drawn over the top of the shuttle between the shuttle and its drive shaft and 15 then draws the loop up about the neck of the bag.

The intermittent cord grip device 14 is caused to grip the cord, at the time the loop take-up operates, by means of an arm 66 mounted on the needle carriage 20 having a cam portion 67 which engages the side of gripping device 14 and forces the gripping disk 68 over toward the gripping disk 69 to cause the cord to be securely held between 25 these grips.

The gripping disk 68 is mounted on a yieldable arm 69^a, the tension in which is such as to normally permit the plate to be readily drawn between the clamping disks 30 68 and 69. However, when the arm 66 moves forwardly the cam portion 67 engages the side of the yieldable arm 69^a and forces the gripping disk 68 toward the gripping disk 69 to hold the cord at this 35 time.

In order to provide a support or backing for the neck of the bag at the time the needle is forcing the cord therethrough, an intermittently operated lever 70 is provided 40 having a foot portion 71 which is brought up against the neck of the bag at just the right time to support it when the needle is forcing its way through the bag. This rock lever is pivoted at 72 on a bracket 73 controlled in its movement by a coil tension 45 spring 74 urging it in one direction and a cam 75 mounted on a rotatable shaft 76, which, at the proper time, operates the lever against the action of this spring.

50 In operation, the conveyor is operated at intervals to bring the bags successively past the bag tying mechanism. The conveyor is brought to a stop with one of the bag carrying guide members 17 just opposite the needle carriage 20 and the loop placing mechanism 13.

The needle carriage 20 is then reciprocated to cause the needle to perforate the gathers at the neck of the bag and force a 55 loop of cord therethrough. At the time the needle perforates the neck of the bag the arm 70 is rocked to bring the foot portion 71 up snugly against the neck of the bag opposite the needle to hold it for the perforating operation. The looper carriage

36 is then reciprocated to bring the axis of the shuttle 37 directly underneath the axis of the shuttle drive shaft 42, the rollers 44 serving to accurately position the looper carriage with respect to the bag carrying 70 device 11. The intermittently rotatable shaft 42 then causes a revolution of the shuttle 37, causing the point of the shuttle to catch the loop of thread from the needle 12 and place it around the neck of the bag. 75 The needle carriage 20 is then withdrawn, the first half of the withdrawal causing the loop take-up arm 34 to act to draw the loop up about the neck of the bag.

The intermittent cord grip 14 holds the 80 cord tightly at the time the loop take-up arm acts, to prevent the cord from feeding at this time.

In the claims where the expression "axis of the bag" is used, it is to be understood 85 as meaning the longitudinal axis extending from top to bottom of the bag.

I claim:

1. A bag tying machine for tying a bag 90 having a gathered neck, the axis of which extends longitudinally of the bag comprising means for forcing a loop of cord through the gathers at the neck of the bag, and means for opening the loop and for placing the loop over the ends of the gathers 95 and causing it to substantially completely encircle the neck of the bag and drawing the loop up about the neck.

2. A bag tying machine for tying a bag 100 having a gathered neck, the axis of which extends longitudinally of the bag comprising a needle for forcing a loop of cord through the gathers at the neck of the bag, and means for opening the loop and for placing the loop over the ends of the gathers and causing it to substantially completely 105 encircle the neck of the bag and drawing the loop up about the neck.

3. A bag tying machine for tying a bag 110 having a gathered neck, the axis of which extends longitudinally of the bag comprising means for forcing a loop of cord through the gathers at the neck of the bag, and rotary means for opening the loop and for placing the loop over the ends of the gathers and causing it to substantially completely 115 encircle the neck of the bag and drawing the loop up about the neck.

4. A bag tying machine for tying a bag 120 having a gathered neck, the axis of which extends longitudinally of the bag comprising a needle for forcing a loop of cord through the gathers at the neck of the bag and rotary means for opening the loop and for placing the loop over the ends of the gathers and causing it to substantially completely 125 encircle the neck of the bag.

5. A bag tying machine for tying a bag 130 having a gathered neck, the axis of which extends longitudinally of the bag com-

prising a conveyor provided with a series of bag carrying and neck gathering devices and a bag tying mechanism past which the bags are carried, comprising a needle which perforates the gathers at the neck of the bag and passes a loop of cord therethrough, and rotary means for opening the loop and for placing the loop over the ends of the gathers and causing it to substantially completely encircle the neck of the bag.

6. A bag tying machine for tying a bag having a gathered neck, the axis of which extends longitudinally of the bag comprising means for gathering the bag at the neck, a needle which perforates the gathers of the bag and passes a loop of cord therethrough, and rotary means for opening the loop and for placing the loop over the ends of the gathers and causing it to substantially completely encircle the neck of the bag.

7. A bag tying machine for tying a bag having a gathered neck, the axis of which extends longitudinally of the bag comprising a conveyor provided with a series of bag carrying devices, a needle for passing a loop of cord through the neck of the bag, and rotary means for opening the loop and for placing the loop over the ends of the gathers and causing it to substantially completely encircle the neck of the bag.

8. A bag tying machine for tying a bag having a gathered neck, the axis of which extends longitudinally of the bag comprising means for passing a loop of cord through the gathers of the neck of the bag and intermittently rotatable means for opening the loop and for placing the loop over the ends of the gathers and causing it to substantially completely encircle the neck of the bag.

9. A bag tying machine for tying a bag having a gathered neck, the axis of which extends longitudinally of the bag comprising an intermittently movable conveyor provided with a series of bag carrying and neck gathering devices and a bag tying mechanism past which the bags are carried comprising a needle which perforates the gathers and forces a loop of cord therethrough during the stationary condition of the conveyor and an intermittently reciprocable loop placing mechanism comprising an intermittently rotatable looper, said loop placing mechanism being reciprocable to bring the axis of the looper in line with the axis of the neck of the bag during the stationary condition of the conveyor and to move the loop placing mechanism out of the way of the conveyor during the intermittent movement of the conveyor.

10. A bag tying machine for tying a bag having a gathered neck, the axis of which extends longitudinally of the bag comprising an intermittently movable conveyor

provided with a series of bag carrying and neck gathering devices and a bag tying mechanism past which the bags are carried comprising a needle which perforates the gathers and forces a loop of cord therethrough during the stationary condition of the conveyor and an intermittently reciprocable loop placing mechanism comprising an intermittently rotatable looper, said loop placing mechanism being reciprocable to bring the axis of the looper in line with the axis of the neck of the bag during the stationary condition of the conveyor and to move the loop placing mechanism out of the way of the conveyor during the intermittent movement of the conveyor, and means for drawing the loop up about the neck of the bag.

11. A bag tying machine for tying a bag having a gathered neck, the axis of which extends longitudinally of the bag comprising an intermittently movable conveyor provided with a series of bag carrying and neck gathering devices and a bag tying mechanism past which the bags are carried comprising a needle which perforates the gathers and forces a loop of cord therethrough during the stationary condition of the conveyor and an intermittently reciprocable loop placing mechanism comprising an intermittently rotatable looper, said loop placing mechanism being reciprocable to bring the axis of the looper in line with the axis of the neck of the bag during the stationary condition of the conveyor and to move the loop placing mechanism out of the way of the conveyor during the intermittent movement of the conveyor, means for gripping the thread being fed to the needle, and means acting on the thread between the gripping means and needle for drawing the loop up about the neck of the bag.

12. A bag tying machine for tying a bag having a gathered neck, the axis of which extends longitudinally of the bag comprising an intermittently movable conveyor provided with a series of bag carrying and neck gathering devices and a bag tying mechanism past which the bags are carried comprising a needle which perforates the gathers and forces a loop of cord therethrough during the stationary condition of the conveyor and an intermittently reciprocable loop placing mechanism comprising an intermittently rotatable looper, said loop placing mechanism being reciprocable to bring the axis of the looper in line with the axis of the neck of the bag during the stationary condition of the conveyor and to move the loop placing mechanism out of the way of the conveyor during the intermittent movement of the conveyor, means for gripping the thread being fed to the needle, and a rock arm acting on the thread between the gripping means and

needle for drawing the loop up about the neck of the bag.

13. A bag tying machine for tying a bag having a gathered neck, the axis of which extends longitudinally of the bag, comprising a conveyor provided with a series of bag carrying and neck gathering devices and a bag tying mechanism past which the bags are carried, comprising a needle which 0 perforates the gathers at the neck of the bag and passes a loop of cord therethrough, and rotary means for opening the loop and for placing the loop over the ends of the gathers and causing it to substantially completely encircle the neck of the bag, said rotary means being coaxial with the bag operated on.

14. A bag closing machine comprising an intermittently movable bag carrying conveyor for carrying the bags in a direction transverse to their axes, means for gathering each bag to form a neck extending longitudinal of the axis of the bag, and a bag tying mechanism past which the bags are 5 carried comprising a needle which perforates the gathers at the neck of the bag and passes a loop of cord therethrough, and rotary means for opening the loop and for placing the loop over the ends of the gathers 0 and causing it to substantially completely encircle the neck of the bag.

15. A bag closing machine comprising a bag carrying conveyor, a series of neck gathering devices mounted on said conveyor and a bag securing device past which the 25 bags are successively carried by the conveyor, each neck gathering device comprising a guide extending transversely of the line of movement of the conveyor, and a pair of jaws mounted in each of said guides 40 to slide transversely of the line of movement of the conveyor.

16. A bag closing machine comprising a bag carrying conveyor, a series of neck gathering devices mounted on said conveyor 45 and a bag securing device past which the bags are successively carried by the conveyor, each neck gathering device comprising a guide extending transversely of the line of movement of the conveyor, and a 50 pair of jaws mounted in each of said guides to slide transversely of the line of movement of the conveyor, each jaw having a converging neck engaging portion, the converging portion of one jaw overlapping the 55 converging portion of the other jaw as the jaws approach each other, whereby the neck of the bag is squeezed together by the converging portions of both jaws.

In witness whereof, I have hereunto subscribed my name.

JULIUS H. WALD.
